US00D963499S

(12) **United States Design Patent** (10) Patent No.: **US D963,499 S**
(45) Date of Patent: **** Sep. 13, 2022**

(54) **MASS SPECTROMETER**

- (71) Applicant: **Micromass UK Limited**, Wilmslow (GB)
- (72) Inventors: **Arthur Blake**, Manchester (GB); **Andrew Pawson**, Manchester (GB); **Edward Scott**, Cheshire (GB); **Emma Marsden-Edwards**, Greater Manchester (GB); **Kate Wearden**, Leyland (GB)
- (73) Assignee: **Micromass UK Limited**, Wilmslow (GB)

(**) Term: **15 Years**

(21) Appl. No.: **29/714,631**

(22) Filed: **Nov. 25, 2019**

(30) **Foreign Application Priority Data**

(57) **CLAIM**

The ornamental design for a mass spectrometer, as shown and described.

DESCRIPTION

FIG. 1 is a perspective view of a mass spectrometer showing the design.

FIG. 2 is a front elevation view of the design.

FIG. 3 is a rear elevation view of the design.

FIG. 4 is a side elevation view of the design; and,

FIG. 5 is a top plan view of the design.

The portions of the mass spectrometer shown in broken lines form no part of the claimed design.

1 Claim, 5 Drawing Sheets
